UNITED STATES PATENT OFFICE

162,824

AMUSEMENT DEVICE

Vallie Hammer, Bell Gardens, Calif.

Application December 18, 1948, Serial No. 150,227

Term of patent 3½ years

(Cl. D34—15)

To all whom it may concern:

Be it known that I, Vallie Hammer, a citizen of the United States, residing in Bell Gardens, in the county of Los Angeles and State of California, have invented a new, original, and ornamental Design for an Amusement Device, of which the following is a specification, reference being had to the accompanying drawing, forming part thereof:

The figure is a perspective view of an amusement device, showing my new design.

The dominant features of the design reside in the parts shown in full lines on the drawing. The rear end of the design is generally conventional. The opposite side, except for the implements mounted on the wagon, is substantially similar to the side that is shown.

I claim:

The ornamental design for an amusement device, substantially as shown and described.

VALLIE HAMMER.
